GOLF PUTTER HEAD

Edward H. Hoglund, 1020 Lois Ave.,
Park Ridge, Ill. 60068

Filed Mar. 23, 1972, Ser. No. 237,613

Term of patent 14 years

Int. Cl. D21—02

U.S. Cl. D34—5 GH

FIG. 1

FIG. 2

FIG. 3

FIG. 4

FIG. 5

FIG. 6

FIG. 1 is a perspective view of a golf putter head showing my new design;

FIG. 2 is a top plan view of the same;

FIG. 3 is a front-on elevational view of the same;

FIG. 4 is a side elevational view of the same;

FIG. 5 is a rear elevational view of the same; and

FIG. 6 is a bottom plan view of the same.

I claim:

The ornamental design for a golf putter head, substantially as shown.
